UNITED STATES PATENT OFFICE.

OTTO H. MOHR, OF OAKLAND, CALIFORNIA, ASSIGNOR TO OHM CO., OF CHICAGO,
ILLINOIS, A CORPORATION OF DELAWARE.

DESIGN FOR A LIGHTING-FIXTURE.

51,021.

Specification for Design. Patented July 10, 1917.

Application filed March 29, 1917. Serial No. 158,476. Term of patent 7 years.

To all whom it may concern:

Be it known that I, Otto H. Mohr, a citizen of the United States, residing at Oakland, in the county of Alameda and State of California, have invented a new, original, and ornamental Design for a Lighting-Fixture, of which the following is a specification, reference being had to the accompanying drawing, forming part thereof.

The figure is a perspective view of a lighting fixture, showing my new design.

My design consists of a canopy having a lower reflecting surface with a central opening for the passage of an electric light bulb,

and an inverted cone-shaped member suspended by a number of spindles secured adjacent its upper edge, said cone-shaped member being formed of a plurality of strips of glass, cut so as to form the cone-shape and placed in spaced relationship at an angle so that the source of light cannot be seen intermediate the glass strips and an ornamental cap at the lower end of said glass strips.

I claim:

The ornamental design for a lighting fixture, as shown.

OTTO H. MOHR.
